UNITED STATES PATENT OFFICE

JAMES S. PHIFER, OF ALLENTOWN, PENNSYLVANIA; ASSIGNOR TO THE AMERICAN STEEL AND WIRE COMPANY, OF NEW JERSEY, OF HOBOKEN, NEW JERSEY, A CORPORATION OF NEW JERSEY.

BUNDLING APPARATUS.

1,242,471.

Specification of Letters Patent.

Patented Oct. 9, 1917.

Application filed May 14, 1917. Serial No. 168,466.

To all whom it may concern:

Be it known that I, JAMES S. PHIFER, a citizen of the United States, and resident of Allentown, in the county of Lehigh and State of Pennsylvania, have invented certain new and useful Improvements in Bundling Apparatus, of which the following is a specification.

This invention relates to bundling and baling apparatus, and has for its object to provide improved means for compressing or drawing together a plurality of strands or the like in a very simple and convenient manner and for holding the same under compression while applying a holding band or clip thereto.

The invention is specifically designed for use in connection with strands wound in the form of a substantially circular bundle, as for instance, coiled bundles of wire as are commonly mounted upon reels for storage and handling of the same.

With these and other objects in view, the present invention consists in the combination and arrangement of parts, as will be hereinafter more fully described, shown in the drawings, and particularly set forth in the appended claims, it being understood that changes in the form, proportion, size and minor details may be made, within the scope of the claims, without departing from the spirit or sacrificing any of the advantages of the invention.

In the drawings,

Figure 1 is a plan view of a bundling apparatus embodying the features of the present invention.

Fig. 2 is a cross-sectional view on line 2—2 of Fig. 1.

Fig. 3 is a cross sectional view on the line 3—3 of Fig. 1.

Fig. 4 is a cross-sectional view on the line 4—4 of Fig. 1.

The present apparatus includes a supporting frame in the form of a table made up of a plurality of radial arms 1, 2, 3 and 4, each of which is supported by means of a

leg or standard 5 secured at its upper end, as at 6, about midway between the inner and outer ends of the arm. A convenient arrangement of arms has been shown in Fig. 1, wherein the diametrically opposite arms 2 and 4 consist of a single bar, while the arms 1 and 3 are independent bars provided at their inner ends with lateral ears or extensions 7 and 8, respectively, which are secured to the arms 2 and 4, respectively, by suitable fastenings 9. The upper faces of the several arms are, of course, in the same horizontal plane so as to form a table top or work support for the work 10 which is in the form of a bundle of coiled strands.

The upper end of each leg standard 5 is received between one of the radial arms and the shank portion 11 of a bracket 12, the fastenings 6 piercing the shank 11, the leg standard 5 and the arm, so as to rigidly connect these parts together. The bracket portion 12 is offset from the shank 11 and provides a suitable space between the arm and the bracket for the accommodation of certain of the working parts of the present apparatus.

In the space or bifurcation defined by the bracket 12 and the adjacent arm there is a ratchet wheel 13 mounted upon a shaft 14 journaled in the bracket and the arm. This shaft projects at opposite ends beyond the arm of the bracket and is provided with a head 15 and at the other end is a nut 16. Between the head 15 and the arm there is a drum 17 fixed to and rotatable with the shaft. Associated with the ratchet wheel 13 is a dog 18 which lies between the bracket 12 and the arm and is carried by a shaft 20 rotatably mounted in the bracket 12 and the arm and provided at one end with a suitable handle 21, preferably in the form of a crank arm, whereby the dog may be engaged with and disengaged from the ratchet wheel 13. The shaft 20 for the dog is mounted at a lower level than the shaft 14, and the dog and the handle 21 are so disposed that the dog is held by gravitation in engagement

with the ratchet wheel, and may be readily disengaged therefrom by swinging the handle away from the ratchet wheel. As indicated in dotted lines in Fig. 4, it will be seen that the dog rests against the adjacent leg standard 5 when thrown out of engagement with the ratchet wheel and is thereby held in position for convenient return to the ratchet wheel.

- 10 For rotating the drum shaft 14, there is provided a ratchet mechanism consisting of a handle 22 provided with a bifurcated head 23 embracing the ratchet wheel and pierced by the shaft 14 on which the handle rotates.
- 15 Within the bifurcated head 23 there is pivoted a dog 24, as at 25, the free end of the dog being disposed for engagement with the ratchet teeth of the wheel. This dog is provided with a handle 26 lying alongside the handle 22 at the inner face thereof, and there is a spring 27 interposed between the two handles to normally hold the dog 24 in engagement with the ratchet wheel. By the proper manipulation of the handle 22, in the 20 well known manner, the ratchet wheel, shaft and drum may be conveniently rotated. The dog 24 may, of course, be disengaged from the ratchet wheel by pressing the handle 26 toward the handle 22, whereupon the ratchet 25 wheel, shaft and drum may be rotated in either direction without interference by the dogs 24 and 18 when the latter has been disengaged from the ratchet wheel.

For each drum, there is a flexible member 35 28, such as a chain, wire cable, rope or the like. One end of this flexible element is made fast to the drum in any suitable manner and is designed to be wound thereon, while the other end of the flexible member 40 is designed to be fixed or anchored to a central portion of the table, whereby a loop 29 in an intermediate portion of the flexible member may be drawn tightly around the bundle to be operated upon. A very satisfactory connection between the flexible member and the table may be had by the provision of a notch or seat 31 in the top of one of the arms and into which the flexible element is dropped, the head or button 45 30 serving as an anchor device to engage the far side of the arm and secure the flexible element thereto when the other end portion of the flexible element is being wound upon the drum.

55 In the operation of the apparatus, the flexible elements are disconnected from the arms of the table and moved out of the way. The bundle 10 is then placed upon the table, and then each of the flexible members is coiled or looped once around the adjacent portion of the bundle, and its free end is secured to the table in the manner hereinbefore described. Each of the drums

is then rotated, by means of its handle 22, so as to draw the loop 29 tightly around the bundle until the latter is compressed to the desired extent, whereupon the loop is held in this condition by means of the dog 18 until a suitable permanent tie or clip has been applied to the bundle, whereupon the flexible member may be released and unwound from the bundle 10 and the latter removed from the table. The several drums may be operated simultaneously or successively as may be desired.

Having thus described the invention, what I claim, is:

1. A bundling machine comprising a work table, a plurality of flexible bundle-embracing members anchored at the middle portion 80 of the table and extending outwardly in different directions therefrom, and means for placing tension upon the flexible members.
2. A bundling machine comprising a table 85 including a plurality of substantially radial arms, a flexible bundle-embracing member for each arm, each of said members having its inner end secured to one of the arms and extending outwardly therefrom, and means 90 associated with the outer end portion of each flexible member to place tension thereon.
3. A bundling machine comprising a work table including a plurality of radial arms, each arm having a notch therein adjacent 95 the middle of the table, a flexible bundle-embracing member for each arm, the inner end portion of each flexible member being received in one of the notches and extending outwardly therefrom, a button on the 100 inner end of said flexible member to prevent the member from being drawn through the notch, and means associated with the outer end of the flexible member for placing strain thereon.
4. A bundling machine comprising a work table including a plurality of substantially radial arms, a winding drum mounted upon the outer end of each arm, a ratchet wheel 110 and dog for the drum, a ratchet lever associated with the ratchet wheel for rotating the drum, a bundle-embracing flexible member having its outer portion connected to the drum, said flexible member extending to the middle of the table and being of a length 115 to permit the formation of a loop therein, and means at the middle of the table for detachably anchoring the flexible member thereto.

5. A bundling machine comprising a table 120 having a plurality of substantially radial arms, each arm being provided adjacent its inner end with a notch in the top thereof, leg standards for the arms, a winding drum mounted at the outer end of each arm, 125 means for rotating the drum, a ratchet de-

vice to prevent unwinding of the drum, and a flexible bundle-embracing member having an end portion connected to the drum and extending inwardly therefrom alongside the adjacent arm and having its inner end portion removably received in the notch of one of the other arms, the inner end of the flexi-

ble member being provided with a button lying at the opposite side of said other arm and of a size to prevent the flexible member 10 from being drawn through the notch.

In testimony whereof I have hereunto set my hand.

JAMES S. PHIFER.
